UNITED STATES PATENT OFFICE

2,665,680

RADIUS DRESSER

Harry H. Gotberg, Detroit, Mich., assignor to
 Colonial Broach Company, Warren Township,
 Mich., a corporation of Delaware

Application December 30, 1950, Serial No. 203,667

9 Claims. (Cl. 125—11)

1

This invention relates generally to a device for dressing grinding wheels and more particularly to a device for dressing the peripheral radius and adjacent tangential flat surface of a grinding wheel.

Many metal working tools such as broaches and the like, require frequent sharpening and resurfacing, and for this purpose an abrasive grinding wheel is generally used. In many instances grinding wheels of the type having a peripheral radius and adjacent tangential flat surface are employed. In the resharpening of broaches it is extremely important that the grinding wheel shape be accurately maintained at all times and that a smoothly dressed wheel be provided so that a keener and smoother broach tooth cutting edge will be provided which in turn will produce a better finish on the broach part. Therefore, grinding wheels must be frequently dressed and a diamond point dresser appears to perform this result in the best manner possible. Many grinding wheel dressing tools and devices have been devised, but these have generally been too expensive to manufacture, too complicated in construction and operation, too difficult for an operator to use for quickly dressing the grinding wheel, and often require complicated and time consuming adjustments as the wheel wears.

It is, therefore, an object of this invention to provide a grinding wheel dressing device which may be mounted adjacent to or on the spindle housing of a grinding wheel, which is sharpening broaches or other similar tools, and which may be moved into or out of engagement with the grinding wheel in a very simple manner, so as to engage the grinding wheel at the proper point for the dressing thereof.

It is a still further object of this invention to provide a dressing tool of the aforementioned type, in which a diamond tip tool is employed for dressing the grinding wheel and in which the peripheral radius of the grinding wheel may be dressed by the actuation of one lever, and the flat surface may be dressed by the actuation of another lever, without the necessity of any special adjustments or complicated aligning of the device with the grinding wheel, and without any concern of the dressing tool not properly dressing the grinding wheel.

It is a still further object of this invention to provide a dressing tool device of the aforementioned type which can dress grinding wheels of different sizes and shapes in a rapid, efficient and simple manner.

It is a still further object of this invention to

provide a dressing device of the aforementioned type, which is mountable on the grinding wheel spindle housing so that irrespective of the adjusted position of the housing and wheel the dresser will be in position to dress the wheel without having its setting disturbed.

It is a still further object of this invention to provide a device of the aforementioned type which is exceptionally simple and inexpensive to manufacture, and is the most simple and efficient to use of all dressing devices of this type heretofore known.

These and other objects of this invention will become apparent from the following detailed description, taken in conjunction with the accompanying drawings, in which:

Fig. 1 is a top plan view of the dressing device of this invention supported in a position to dress a grinding wheel.

Fig. 2 is a side elevational view of the structure illustrated in Figure 1 showing the dresser disposed above a wheel to be dressed.

Fig. 3 is a reduced side elevational view showing the dressing device mounted on the spindle housing of a grinding wheel.

Fig. 4 is an end elevational view of the structure illustrated in Fig. 3.

Fig. 5 is an enlarged sectional view of the structure illustrated in Figure 1, taken along the line 5—5 thereof;

Fig. 6 is an enlarged sectional view of the structure illustrated in Fig. 2, taken along the line 6—6 thereof;

Fig. 7 is a sectional view of the structure illustrated in Fig. 2 taken along the line 6—6 thereof;

Fig. 8 is a front elevational view of a portion of the device of this invention, showing the diamond tip in engagement with the peripheral radius of a grinding wheel at the start of the dressing operation;

Fig. 9 is a view similar to Fig. 8, showing the position of the parts after the peripheral radius of the wheel has been partially dressed; and

Fig. 10 is a view similar to Figs. 8 and 9, showing the position of the parts after the radius has been dressed and before the grinding wheel tangential flat surface has been dressed.

Referring now to the drawings, it will be seen that the dressing device is illustrated at 1 and is supported on the upper end of a post 2, the lower end of which is removably and adjustably connected at 3 with a holder and dust shield 4, which in turn is connected with the body or housing 5 of spindle 6, which rotatably drives a

grinding wheel 7 for sharpening broaches or the like. The dressing device 1 includes a horizontally extending support member 8, which comprises an inner elongated, platelike portion 9 from which an outwardly extending square shaft-like portion 10 extends.

The shaft portion 10 extends slidably through an opening 11 of a blocklike member 12. The blocklike member 12 abuts one side of a second blocklike member 13, which is supported on the upper end of the post 2 in a manner which will hereinafter appear. The block members 12 and 13 are secured together by means of a nut and bolt 14, and a pin 15 is supported in the block member 12 and one end thereof extends above a shoulder or stop surface 16, below the top surface of block 13. The shoulder or surface 16 engages the pin 15 when the block members are in their normally disposed aligned, side by side position. By loosening the nut and bolt 14 the block member 12 may be swung about the axis of the bolt relative to the block member 13 so as to swing the dressing device upwardly away from the grinding wheel, for reasons which will hereinafter appear. The pin 15 therefore acts as a locator or stop to enable quick positive realignment of the block members 12 and 13 when the device is to be used to dress a grinding wheel.

The shaft portion 10 of the member 8 has a gear rack 17 secured to the bottom face or side thereof, which meshes with a gear 18 mounted on a shaft 19 which projects through the front side of the block member 12, and has an operating knob 20 connected therewith. If the knob 20 is rotated, the member 8 will be adjusted horizontally relative to the post 2. A set screw 21 is provided in the upper portion of the block member 12, and adapted to engage the shaft portion 10 to lock the dressing device in any adjusted position against accidental horizontal movement. The upper end of the post 2 extends through a vertical opening 22 in the block member 13 and has a gear rack 23, secured to one vertical face thereof, which meshes with a gear 24 carried on a shaft 25 which has one end extending beyond the back face of the block member 13. An operating knob 26 is connected with the projecting portion of the shaft and may be rotated to adjust the block members 12 and 13 vertically on the post. A set screw 27 is threaded into block member 13 for engaging the post 2 to positively lock the block members and the dressing device in any adjusted position relative to the post. Thus, with the aforementioned construction, the dressing device may be adjusted horizontally and vertically relative to the post, for reasons which will hereinafter appear.

A housing member 29 is adjustably secured to one face of the plate portion 9 of the member 8, by any suitable means such as cap screws 31, as will be hereinafter described. The outer face of the housing is suitably recessed at 33 to provide ways in which a movable slide element 35 is positioned. Gibs 37 are secured to the outer face of the housing 29 by cap screws 38 to retain the movable slide member 35 within the ways and guide its vertical movement. A gear rack 29 is secured to one side face of the movable element 35 and meshes with a gear 41, which is rotatably supported in the housing by a suitable pin or shaft 43. One end of the pin or shaft 43 extends outwardly through the housing 29 and a gib 37, and has a handle 45 connected thereto which, when actuated, will rotate the gear 41 to

cause the slide element 35 to move vertically in the housing ways 33.

The direction or angle of movement of the slide element 35, may be varied or adjusted by 5 rotatably adjusting the housing 29 on the supporting member 8. This is accomplished by loosening the cap screws 31, one of which extends through an arcuate slot 47 in the plate portion 9 of the member 8, and the other of which is 10 located adjacent the center of the slide element. After the cap screws 31 are loosened the housing 29 can be rotated about the center cap screw 31 to the desired rotative position with respect to the supporting member 8, and in order to accurately determine this relationship the member 8 is provided with an index scale 49. A leaf spring 51 is provided for frictionally retaining the movable element 35 in its adjusted vertical position, and the spring is disposed in a recess 53 in the 15 housing and engages the opposite side face of the movable element from that on which the gear rack 39 is mounted. If the handle 45 is actuated, the slide element 35 will be moved up and down relative to the housing 29, for reasons 20 which will hereinafter appear.

A pair of spaced parallel links 55 and 57 are disposed adjacent the outer face of the slide element 35 and extend generally in the direction of the slide element 35, although they do not necessarily extend parallel to the direction of the movement of the slide element. The links are provided with inwardly extending projection portions 59, 61 and 63, which are spaced from each other equal distances lengthwise of the links, and the projection portions 61 are disposed intermediate the ends of each link and the projection portions 59 and 63 are disposed adjacent the upper and lower ends of each link, respectively. Disposed between the outer face of the slide element 35 and the upper ends of the links 55 and 57, is an inverted triangularly shaped plate element 65. The opposite ends of the base of member 65 are pivotally connected to the opposed projection portions 59 of the links 55 and 57, by means of suitable pivot pins or cap screws 67, and the lower or apex end of the member 65 is pivotally connected to the outer face of the slide element 35 by means of a pivot pin or cap screw 69. A similar inverted triangularly shaped plate member 71 is disposed below the triangular member 65, between the links 55 and 57 and the slide element 35, and has the opposite ends of its base pivotally connected to the link projection portions 61 by means of suitable cap screws or pivot pins 73 and its apex end pivotally connected with the slide element by means of a suitable pivot pin or cap screw 75. A third member 77 extends between the lower ends of links 55 and 57 and is pivotally connected to the projection portions 63 of the links by means of suitable pivot pins or cap screws 79. While the member 77 may be of any suitable shape, it is illustrated, as can be best seen in Fig. 6, as having an outwardly projecting horizontal portion 81, which has a threaded vertically extending aperture 83 therein, in which the upper end of a tool holder 85 is threaded. The tool holder 85 may be vertically adjusted in the member 77 and can be secured in a desired position by means of a set screw 89. The tool holder 85 is centrally bored at 91 and a rod 93 is inserted into the lower end of the bore and carries a diamond tip 95 on the lower end thereof. Set screw 97 secures the rod in the tool holder 85. The tool holder 85 may be threaded inwardly or outwardly in member 77 for reasons

which will hereinafter appear and a button 98 is disposed in the upper end of aperture 83 and is used as a base point to measure or determine the adjusted position of the diamond tip.

It will be noted that the pivot pins or cap screws 61, 73 and 79 connected with each link, are in alignment with each other and are equally spaced from each other lengthwise of the links 55 and 57. It will also be noted that the cap screws or pivot pins 69 and 75 are preferably disposed in alignment with the diamond tip 95 and are spaced equal distances from the cap screws 67 and 73, respectively. A handle or lever 99 is connected with the upper triangular member 65 and when actuated will rotate the members 65 and 71 on the movable slide 35, so as to cause the parallel links 55 and 57 to swing in a parallel relationship at all times, so as to move the member 71 and the diamond tip 95 about a predetermined radius. If the diamond tip 95 is disposed the same distance below the cap screws 79 as the cap screws 69 and 75 are disposed below the cap screws 67 and 73 respectively, the diamond tip will move about a point or center and will not scribe a radius of any dimension. If the tool holder 85 is adjusted so as to move diamond tip 95 above the aforementioned point or theoretical center, it will scribe a radius about the center point in accordance with its adjusted distance above the center point. If the diamond tip is moved below the center point, it will scribe a reverse or concave radius about the center point, in accordance with its adjusted position. Therefore, the diamond tip 95 will move about a radius in accordance with its adjusted position to the theoretical center point of member 71, when the handle 99 is moved to actuate the members 65 and 71 and the links 55 and 57 pivotally connected therewith.

The device of this invention can be used to dress grinding wheels of various types and shapes, but the grinding wheel 7 is illustrated in Figs. 8-10 as having a peripheral radius 103 and an adjacent flat surface 105, which extends tangentially from one side of the radius 103. In order to dress the grinding wheel radius 103 and surface 105, the housing 29 is rotated relative to the supporting member 8, so that the slide element 35 will move in a direction parallel to the grinding wheel flat surface 105. The device is then positioned, by rotating knobs 20 and 26 so that when the handle 45 is actuated to bring the diamond tip downwardly, the tip will engage the grinding wheel radius 103. By then adjusting the diamond tip rod holder 85 relative to member 71, so as to position the tip 95 a predetermined distance from the button 98 and thus from the point or center about which it will rotate, in accordance with the size of the radius of the grinding wheel, the device is ready to dress the grinding wheel and will not require further adjustments. The lever 99 is then actuated so as to position the diamond tip in engagement with the radius 103, as shown in Fig. 8, and by moving the lever 99 counterclockwise, as viewed in Figs. 8 and 9, the diamond tip will move over the grinding wheel peripheral edge or radius 103 to properly dress the same, and when the lever is, as shown in Fig. 10, in its fully swung position, so that the links are in engagement with each other and cannot move any further, the axis of the diamond tip rod 93 will be at right angles to the direction of movement of the slide element 35, and thereafter the diamond tip 95 will be disposed at right angles to the grinding

wheel flat surface 105. The links are so spaced and so interconnected that the diamond tip will be so positioned when the links have moved their maximum distance and engage each other. By then actuating the lever 45, so as to move the slide element 35 downwardly, the diamond tip will move along the flat surface 105 to properly dress the same. The flat surface on the opposite side of the wheel from surface 105 could, of course, also be dressed, if the housing member 29 were rotated so that the slide member would move parallel thereto. This would, of course, require a change of setting of the device.

It will thus be seen that once the dressing device has been mounted on the grinding wheel spindle housing, and adjusted as described above, the operator thereafter need not make any adjustments on the device, except the minute adjustments with knobs 20 and 26 and only need to bring the diamond tip into engagement with the peripheral edge of the grinding wheel and swing the lever 99 so as to cause the parallelogram linkage to move the diamond tip about the desired radius, and then thereafter actuate the lever 45 so as to move the diamond tip along the grinding wheel flat surface 105 so as to dress the same. The dressing device can be moved out of interference with the grinding wheel and the sharpening of the broach or the like may be continued without interference from the dressing device, by loosening nut and bolt 14 and swinging block member 12 and the device upwardly away from the grinding wheel. When it is desired to again dress the wheel the device and block member 12 is swung downwardly until pin 15 engages the shoulder or stop surface 16. The nut and bolt 14 is then tightened and adjustments made by actuating knobs 20 and 26 to insure that the diamond tip will properly engage and dress the wheel. The grinding wheel is then dressed by operating levers or handles 45 and 99. After the wheel is dressed the device can again be moved out of interfering relation with the wheel and the grinding operation on the broach can be continued. The dressing device of this invention therefore permits an operator to quickly and easily dress the grinding wheel in a positive and efficient manner and to a positive and definite form, without the necessity of spending any appreciable time to carry out the dressing operation. Also as the device of this invention is mounted on the grinding wheel spindle body or housing, the setting of the dresser will not be disturbed if the grinding wheel and spindle body are swung at an angle, either horizontally or vertically, as is necessary in the sharpening of broaches or the like, whether the latter be cylindrical or flat. Thus the wheel dressing operation can take place in any angular position of the grinding wheel spindle without remounting or removing the dresser.

What is claimed is:

1. A device for dressing the radiused peripheral edge and adjacent flat surface of a grinding wheel, including supporting structure adapted to be mounted adjacent to the grinding wheel, elongate guides carried by said supporting structure, a movable element mounted in said guides on said supporting structure for rectilinear movement in a predetermined direction parallel to the flat surface of the grinding wheel, a pair of parallel spaced links adjacent said element on the side away from said supporting structure, three transversely extending members spaced from each other in the direction of the length

of said links, means pivotally connecting each of said members with each of said links, means pivotally connecting two of said members to said movable element, means carried by said third member for carrying and supporting a tool for dressing said grinding wheel, and handle means connected with one of said two members for rotating said members and links on the movable element, whereby a parallelogram linkage arrangement is provided, which, when said handle is actuated, will move said third member and a dressing tool when the latter is connected therewith, so that said dressing tool will travel on a predetermined radius to dress said radiused peripheral edge of the grinding wheel, and whereby said element may thereafter be actuated to cause the tool to dress the flat surface of said grinding wheel, said third member being disposed adjacent one end of said element so that said element will be out of interfering relationship with respect to a grinding wheel being dressed.

2. A device for dressing a grinding wheel radiused peripheral edge and an adjacent flat surface which extends tangentially from said radiused peripheral edge, including supporting structure adapted to be mounted adjacent to the grinding wheel, elongate guides carried by said supporting structure, a movable element mounted in said guides on said supporting structure for rectilinear movement in a predetermined direction parallel to the flat grinding wheel surface, a pair of parallel links adjacent said movable element on the side away from said supporting structure and spaced from each other transversely of the longitudinal axis of the movable element, a pair of members spaced from each other longitudinally of said links, pivot pin means pivotally connecting each of said members to each of said links, pivot pin means connecting each of said members to said movable element, said last pivot pin means being spaced longitudinally of said links from the pivot pin means connected to said links, a third member spaced from said two members longitudinally of said links, pivot pin means connecting said third member to each of said links, said pivot pin means connecting said first, second and third members to said links being equally spaced from each other and being in alignment with each other, a grinding wheel dressing tool carried by said third member and being adapted to have the working portion thereof disposed in alignment with the pivot pin means connecting said first and second members to said movable element, one end of said dressing tool being disposed beyond the adjacent end of said element so that said element will be out of interfering relationship with respect to a grinding wheel being dressed, handle means connected with one of said members for actuating the parallel linkage system for rotating said members about the pivot pin means connecting them to said movable element so that movement of said handle will cause said dressing tool to follow a predetermined arcuate path for dressing the radiused peripheral edge of the grinding wheel, after which said element may be actuated to cause said dressing tool to dress the adjacent flat surface of said grinding wheel.

3. A device for dressing a peripheral radiused edge and adjacent flat tangential surface of a grinding wheel, including supporting structure adapted to be mounted adjacent to the grinding wheel, elongate guides carried by said sup-

porting structure, a movable element mounted in said guides on said supporting structure for rectilinear movement in a predetermined direction parallel to the flat surface of the grinding wheel, a pair of parallel links spaced generally transversely of said element and disposed adjacent thereto on a side away from said supporting structure, a triangularly shaped member disposed between said links and said movable element adjacent one end of said links, pivot pin means pivotally connecting said links to said triangular member adjacent the opposite ends of the base of said triangular member, pivot pin means connecting said movable element to said triangular member adjacent the apex thereof, a second triangular member disposed between said links and movable element intermediate the ends of said links, pivot pin means pivotally connecting said links to said second triangular member adjacent opposite ends of the base thereof, pivot pin means pivotally connecting said movable element to said triangular member adjacent the apex thereof, the pivot pin means connecting each of said triangular members to said links being spaced lengthwise of said links the same distance from the respective pivot pin means connecting each of said triangular members to said movable element, a member extending between said links adjacent the opposite end thereof, pivot pin means pivotally connecting said third member to said links, the pivot pin means pivotally connecting said links to said first, second and third members being equally spaced lengthwise of said links, said third member being adapted to carry a tool for dressing the grinding wheel, said third member being disposed adjacent one end of said element so that said element will be out of interfering relationship with respect to a grinding wheel being dressed, handle means connected with one of said members and actuatable to cause said first and second members to rotate on said movable element and impart rotative motion through said links to said third member to cause a dressing tool carried thereby to move through a predetermined arc, so as to dress the radius of the grinding wheel, while thereafter said movable element may be moved parallel to the tangential flat surface of said grinding wheel to dress the same.

4. A device for dressing a peripheral radius and adjacent tangential flat surface of a grinding wheel, including supporting structure adapted to be mounted adjacent to the grinding wheel, elongate guides carried by said supporting structure, a movable element mounted in said guides on said supporting structure for rectilinear movement in a predetermined direction parallel to the flat surface of the grinding wheel, a pair of parallel spaced links adjacent to the said movable element on a side away from said supporting structure, a member extending between and pivotally connected to said links, a dressing tool carried by said member, one end of said dressing tool being disposed beyond one end of said element so that said element will be out of interfering relationship with respect to a grinding wheel being treated, two additional members extending between and pivotally connected to said movable element and to said links to maintain said link in a parallel relationship at all times and to cause said links to move in a predetermined path relative to said movable element so as to cause the working portion of said tool to follow a predetermined radius when said links are actuated.

5. A device for dressing a peripheral radius and adjacent tangential flat surface of a grinding wheel, including supporting structure adapted to be mounted adjacent to the grinding wheel, elongate guides carried by said supporting structure, a movable element mounted in said guides on said supporting structure for rectilinear movement in a predetermined direction parallel to the flat surface of the grinding wheel, a pair of parallel spaced links adjacent to said element on a side away from said supporting structure, three transversely extending members spaced from each other in the direction of the length of said links, means pivotally connecting each of said members with each of said links, means pivotally connecting two of said members to said movable element, a grinding wheel dressing tool carried by said third member, one end of said dressing tool being disposed beyond one end of said element so that said element will be out of interfering relationship with respect to a grinding wheel being dressed, and means connected with one of said members for actuating said links and connected members so as to cause said members to rotate on said movable element and thereby cause said third member and the dressing tool carried thereby to rotate about a predetermined radius, said links and members being so spaced that when said links are moved in one direction so as to engage each other, the tool carried by said third member will be disposed at right angles to the direction of movement of the movable element.

6. A device for dressing a peripheral radius and adjacent tangential flat surface of a grinding wheel, including supporting structure adapted to be mounted adjacent to the grinding wheel, a slide supporting member, means connecting said slide supporting member with said supporting structure for angular adjustment relative thereto, a slide element, means connecting said slide element with said slide supporting member to permit said slide element to move relative to said supporting member in a predetermined lineal direction parallel to the flat surface of the grinding wheel, a gear rack connected with said slide element, a gear rotatably supported on said supporting member and adapted to be rotated so as to move said slide element relative to said supporting member, a pair of parallel spaced links adjacent said element, three transversely extending members spaced from each other in the direction of the length of said links, means pivotally connecting each of said members with each of said links, means pivotally connecting two of said members to said slide element, a grinding wheel dressing tool carried by said third member, and means connected with one of said members for actuating said links and connected members so as to cause said members to rotate on said slide element and thereby cause said third member and the dressing tool carried thereby to rotate about a predetermined radius.

7. A device for dressing the radiused peripheral edge and an adjacent flat surface of a grinding wheel, including post means for supporting the device in a desired location relative to the grinding wheel, a member movably mounted on said post means, cooperating means on said post means and said member actuatable to adjust the position of said member on said post means, an element supported in said member for movement in a direction transversely of the direction of movement of said member on

said post means, cooperating means connected with said element and said member actuatable to adjust the position of said element relative to said member, slide means mounted on said element for movement in a predetermined direction, a pair of parallel spaced links adjacent to said slide means, three transversely extending members spaced from each other in the direction of the length of said links, means pivotally connecting each of said members with each of said links, means pivotally connecting two of said members to said movable slide means, said third member being adapted to carry and support a tool for dressing said grinding wheel, and handle means connected with one of said two members for rotating said members and links on said slide means.

8. A device for dressing a peripheral radius and adjacent tangential flat surface of a grinding wheel, including supporting structure adapted to be mounted adjacent to the grinding wheel and defining elongate guides, an element mounted in said guides for rectilinear movement in a predetermined direction parallel to the flat surface of the grinding wheel, a pair of parallel spaced links adjacent to said element on a side away from said supporting structure, three transversely extending members spaced from each other in the direction of the length of said links, means pivotally connecting each of said members with each of said links, means pivotally connecting two of said members to said movable element, a grinding wheel dressing tool carried by said third member, one end of said dressing tool being disposed beyond one end of said element so that said element will be out of interfering relationship with respect to a grinding wheel being dressed, and means connected with one of said members for actuating said links and connected members so as to cause said members to rotate on said movable element and thereby cause said third member and the dressing tool carried thereby to rotate about a predetermined radius.

9. A device for dressing a peripheral radius and adjacent tangential flat surface of a grinding wheel, including supporting structure adapted to be mounted adjacent to the grinding wheel, elongate guides carried by said supporting structure, a slide element mounted on said supporting structure for rectilinear movement in a predetermined direction parallel to the flat surface of the grinding wheel, means including a rack and gear for moving said element, means connected with said supporting structure and said element permitting said element to be angularly adjusted about said gear relative to said supporting structure and locked in a predetermined angular position, a pair of parallel spaced links adjacent to said element on a side away from said supporting structure, three transversely extending members spaced from each other in the direction of the length of said links, means pivotally connecting each of said members with each of said links, means pivotally connecting two of said members to said movable element, said third member carrying means adapted to support a grinding wheel dressing tool, said third member being disposed adjacent one end of said element so that said element will be out of interfering relationship with respect to a grinding wheel being dressed and means operatively connected with said links for actuating said links and connecting members so as to cause said members to rotate on said movable element and

11

thereby cause said third member and the dressing tool carried thereby to rotate about a predetermined radius.
